UNITED STATES PATENT OFFICE.

BERNARD BRANOWER AND GEORGE BRANOWER, OF NEW YORK, N. Y.

GUIDE FOR HEMMING.

No. 909,533.

Specification of Letters Patent. Patented Jan. 12, 1909.

Application filed November 29, 1907. Serial No. 404,240.

To all whom it may concern:

Be it known that we, BERNARD BRANOWER and GEORGE BRANOWER, citizens of the United States, and residents of the city of 5 New York, borough of the Bronx, in the county and State of New York, have invented a new and Improved Guide for Hemming, of which the following is a full, clear, and exact description.

10 The invention relates to sewing machines having hemming attachments and its object is to provide a new and improved guide for guiding the fabric to the hemming attachment in such a manner as to require practically no attention, thus enabling the operator to attend to a number of sewing machines.

15 The invention consists of novel features and parts and combinations of the same, which will be more fully described herein- 20 after and then pointed out in the claims.

25 A practical embodiment of the invention is represented in the accompanying drawings forming a part of this specification, in which similar characters of reference indicate corresponding parts in all the views.

30 Figure 1 is a cross section of the improvement as applied to a sewing machine having a hemming attachment, the section being on the line 1—1 of Fig. 2; Fig. 2 is a sectional plan view of the same on the line 2—2 of Fig. 3; Fig. 3 is a rear face of the improvement, part being in section, and Figs. 4 and 5 are face views of modified forms of the 35 guide arms.

35 The sewing machine A is provided with a hemming attachment B of any approved construction, for folding a portion C of the fabric material C over, to be subsequently sewed by the sewing machine A with a view 40 to form the hem in the usual manner. In order to guide the material C to the hemming attachment B in such a manner that no further attention is required on the part of the operator, the following arrangement

45 is made: On the front of the table D of the sewing machine A is secured a bracket E, to which is secured a vertically-disposed support F in the form of a plate, to the lower end of which is connected by hinges G, a 50 front guide plate H, extending upwardly and forwardly, and adjustably connected by a rod I with the support F at one end thereof; the said rod I extending through a keeper I' attached to the support F, and

55 which keeper is provided with a clamping screw I' for engaging the rod I, to fasten the

same in place on the support F, thus holding the front guide plate H in a desired angular position relative to the support F. The front guide plate H is provided with a longitudinally-extending slot H', located near its upper end and through which passes the fabric material C in a flat condition. 60

The support F is provided with an opening 'F' in which is held vertically adjustable a guideway J, adapted to be secured in an adjusted position by clamping bolts J' extending through vertically-disposed slots F² formed in the support F, as indicated in Fig. 3. In the guideway J is mounted to 70 slide longitudinally a guide arm K made L-shape, and having an angular or V-shaped slot K' through which passes the fabric material C, after the latter leaves the slot H' in the front plate H. The slot K' extends with 75 its horizontal portion in the front of and adjacent to the front end of the guiding member B' of the hemming attachment B, as plainly indicated in Fig. 1. The guide arm K is adapted to be fastened to the guideway 80 J by a clamping bolt K² passing through a longitudinally-extending slot J² formed in the said guideway J, see Fig. 3. Now by the arrangement described, the guideway J can be adjusted up and down and the guide arm 85 K can be adjusted longitudinally, so as to bring the fabric material into the proper relation relative to the hemming attachment B, as indicated in Figs. 1 and 2.

90 Gages L and L' are held by set screws L² on the guide arm K and the front guide plate H, at the slots K', H', so as to guide the non-hemmed edge of the fabric in the direction of the travel of the fabric, as will be readily understood by reference to Fig. 2. 95

99 The slot H' projects a distance beyond the angular end of the slot K' (see Fig. 2), so that when the fabric material C passes through the slot H' in a flat condition and through the slot K' it is bent up in the angular portion of the slot K' and the bent up portion is delivered to the guide member B' of the hemming attachment B, so that the portion to be hemmed receives an initial turning over in the slot K', to be finally turned completely over on to the hemming attachment B. It will be understood that after a piece of fabric material is started through the guide on the hemming attachment B no further attention is required on 105 the part of the operator, as the guide insures a proper feeding of the material in a 111

partly turned over condition onto the hemming attachment B.

The slot K' in the guide arm K can be varied to suit the form to be given to the portion to be hemmed; thus the slot may be varied as indicated in Figs. 4 and 5. For a narrower or wider fabric material the gages L, L' are adjusted on the guide arm K and the plate 11, as previously explained.

Having thus described our invention, we claim as new and desire to secure by Letters Patent:

1. In combination, a sewing machine having a hemming attachment, and a guide having guiding members one in front of the other for the passage of the fabric material to be hemmed, the rear guiding member having an angular slot for turning a portion of the fabric material up and delivering it to the hemming attachment.

2. In combination, a sewing machine having a hemming attachment, and a guide having guiding members one in front of the other for the passage of the fabric material to be hemmed, the rear guiding member having an angular slot and the front member having a straight slot, the fabric material passing through the said slots and having a portion turned up in its passage through the angular slot of the rear member.

3. In combination, a sewing machine having a hemming attachment, and a guide having guiding members one in front of the other for the passage of the fabric material to be hemmed, the rear guiding member having an angular slot and the front member having a straight slot, the fabric material passing through the said slots and having a portion turned up in its passage through the angular slot of the rear member, one end of the slot in the front member projecting beyond the angular end of the slot in the rear member.

4. In combination, a sewing machine having a hemming attachment, a guide having guiding members one in front of the other for the passage of the fabric material to be hemmed, the rear guiding member having an angular slot and the front member having a straight slot, the fabric material passing through the said slots and having a portion turned up in its passage through the angular slot of the rear member, one end of the slot in the front member projecting beyond the angular end of the slot in the rear member, and adjustable gages on the said members and extending across the slots to guide the non-hemmed edge in a straight line running in the direction of the travel of the material.

5. A guide for a sewing machine having a hemming attachment, comprising a vertical support for attachment to the sewing machine, and a guide arm held on the said support and provided with an angular slot for the passage of the fabric material to turn

up a portion of the said material and deliver it to the hemming attachment.

6. A guide for a sewing machine having a hemming attachment, comprising a vertical support for attachment to the sewing machine, a guide arm held on the said support and provided with an angular slot for the passage of the fabric material to turn up a portion of the said material and deliver it to the hemming attachment, and means for adjusting the said guide arm longitudinally.

7. A guide for a sewing machine having a hemming attachment, comprising a vertical support for attachment to the sewing machine, a guide arm held on the said support and provided with an angular slot for the passage of the fabric material to turn up a portion of the said material and deliver it to the hemming attachment, and means for adjusting the said guide arm up and down.

8. A guide for a sewing machine having a hemming attachment, comprising a vertical support for attachment to the sewing machine, a guide arm held on the said support and provided with an angular slot for the passage of the fabric material to turn up a portion of the said material and deliver it to the hemming attachment, means for adjusting the said guide arm longitudinally, and means for adjusting the said guide arm up and down.

9. A guide for a sewing machine having a hemming attachment, comprising a support for attachment to the sewing machine, a guide arm held on the said support and provided with an angular slot for the passage of the fabric material to turn up a portion of the said material and deliver it to the hemming attachment, and a plate hinged to the said support and extending in the front of the said support, the said plate having a slot for the passage of the fabric material.

10. A guide for a sewing machine having a hemming attachment, comprising a support for attachment to the sewing machine, a guide arm held on the said support and provided with an angular slot for the passage of the fabric material to turn up a portion of the said material and deliver it to the hemming attachment, a plate hinged to the said support and extending in the front of the said support, the said plate having a slot for the passage of the fabric material, and means for adjustably securing the said hinged plate in position relative to the said support.

11. In a guide for sewing machines, a support, a vertically adjustable guideway carried by the support, and a horizontally adjustable guide arm carried by the guideway and having an angular slot.

12. In a guide for sewing machines, a plate having an opening therein, a guideway in the opening, means for adjusting the guideway vertically in said opening, a guide arm

mounted in the guideway and having an angular slot, and means for adjusting the guide arm horizontally in the guideway.

13. A hem folder comprising a flat, folding plate arranged in a vertical plane and having a V-shaped slot passing therethrough, and means for directing the material to be folded through said slot.

In testimony whereof we have signed our names to this specification in the presence of two subscribing witnesses.
